DESIGN FOR A LIGHT DIFFUSER

Charles H. Nehls, Detroit, Mich.

Application September 22, 1937, Serial No. 71,719

Term of patent 7 years

To all whom it may concern:

Be it known that I, Charles H. Nehls, a citizen of the United States and a resident of Detroit, in the county of Wayne and State of Michigan, have invented a new, original, and ornamental Design for a Light Diffuser, of which the following is a specification, reference being had to the accompanying drawing, forming part thereof.

Fig. 1 is a perspective view of the light diffuser shown on a lamp to indicate its appearance when in use, showing my new design.

I claim:

The ornamental design for a light diffuser, as shown and described.

CHARLES H. NEHLS.
